U.S. Cl. D26—14 A

The single figure is an elevational perspective view of a telephone instrument stand showing my new design.

The two sides of the stand are alike and the rear side and the bottom side of the stand are plain and have a rectangular outline.

This is a division of application Ser. No. D-130,063 filed Mar. 31, 1971.

I claim:

The ornamental design for stand for a telephone instrument, as shown and described.
